R. C. Hamilton

UNITED STATES PATENT OFFICE.

GEORGE F. NEWTON, OF KANSAS CITY, MISSOURI, ASSIGNOR OF ONE-HALF TO
SEBASTIAN PATTI, OF KANSAS CITY, MISSOURI.

CAM COLUMN CLAMP.

Application filed October 18, 1926. Serial No. 142,418.

This invention relates to cam operated form clamps for use in the construction of concrete columns and the like, and has for one of its objects to produce a cam clamp 5 for co-operation with rectangular form bars, in which the cam preferably is formed with a smooth face and will therefore give indefinite service and will operate to impress a bar to be clamped against a set of removable teeth co-operating with said cam lug.

A further object is to produce a strong, efficient, durable, and inexpensive cam column clamp, and in order that it may be fully understood, reference is to be had to 15 the accompanying drawing, in which:—

Figure 1 is a section taken through a concrete form equipped with clamps embodying the invention.

Figure 2 is a side elevation of the same. 20 Figure 3 is an enlarged detail of one of the cam clamps to illustrate the removable toothed lug carried by one end of each of the clamp bars.

Figure 4 is an enlarged section on the 25 line IV—IV of Figure 1.

Figure 5 is a section on the line V—V of Figure 1.

Figure 6 is an inverted plan view of the mechanism shown in Figure 5.

30 In the said drawing where like reference characters identify corresponding parts in all of the figures, the form clamps of the invention comprise a series of four rectangular bars 1 of any desired length in excess 35 of the width of the form, and secured to the opposite faces of one of the ends of each bar is a pair of extensions 2 to form a bifurcated portion for the reception of the straight end of an adjacent bar, as will hereinafter appear. Received between the extensions 2 adjacent the end of the bar 1 and held in position by a rivet 3, is a lug 4 formed on its opposite faces with suitably hardened teeth 5, for a purpose which will 40 hereinafter appear, and mounted in the free ends of the extensions 2 is a pivot pin 6, on which is rotatably mounted between said extensions 2, a lever 7 formed with a cam face 8.

50 The operation of the clamp bars of the invention for the locking of a concrete column form, is, as follows: The clamp bars are assembled around the form as shown in

Figure 1 and as common in the art the operator will then clamp the bars successively 55 against the form, by the use of any suitable mechanism, such as that illustrated, which comprises a relatively U-shaped member 9 placed on the projecting straight end of one of the clamp bars and formed with a series of internal teeth 10 for frictional engagement with the inner edge of said bar, the U-shaped member 9 carrying at its opposite end from said teeth 10 a clamp lever 11 formed at its pivoted end with a cam face 12 for pressing against the extension-equipped end of the bar it is desired to adjust or clamp against the form. It will be apparent that by pressing downwardly on the lever 11 arranged as illustrated in Figure 5, its cam face 12 will press against the extension portion 2 and will tend to press the crossed bars 1 in opposite directions, as shown in Figure 1. As soon as the desired clamping pressure has been exerted at one 75 corner, the operator will lock the bars at such corner in position by striking the lever 7 and thus causing its cam 8 to push the side-wise abutting bar 1 until the teeth 5 are strongly engaged with said clamp bar to 80 prevent any possibility of relative slipping movement of the parts. The operator will then proceed to tighten the other corners of the form in a similar manner.

It will be evident that the concrete form 85 clamps can be readily and easily unlocked by placing the claws of a hammer or the like under the projecting ends of the cam lever 7 and pressing upwardly. If there is any tendency of the teeth 5 to jam or stick 90 to the engaged end of one of the bars 1, it will be apparent that this tendency can be readily overcome and the bars loosened by tapping gently against the engaged ends of such wedged or locked bar 1 so that it may 95 be withdrawn from engagement with said teeth 5. It will also be evident that if the teeth 5 on either face of the lug 4 become worn to such a degree as to fail in positively locking the clamp bars, the unworn 100 face may be readily disposed in position for operative engagement by knocking out the rivet 3 and reversing the position of said lug 4.

From the above description, it will be 105 evident that while I have described and

illustrated the preferred embodiment of the invention, it is to be understood that I reserve the right to make all changes which properly fall within the spirit and scope of the appended claims.

I claim:

1. In a concrete column clamp, a flat bar, a pair of flat bars fitting against opposite sides of the first-named bar and projecting beyond one end of the same to provide a fork therefor, a lug secured in the fork and against the extremity of the first-named bar so as to be incapable of turning or accidental dislodgment, and provided on its outer edge with a series of vertical teeth facing toward the open end of the fork, and a pivoted cam clamp spaced from the lug and mounted in the fork, to clamp an object extending cross-

wise through the fork, inwardly against the outwardly-facing teeth of said lug.

2. A concrete column clamp, comprising a series of bars arranged to form a rectangle, each bar having one end forked and receiving the unforked end of an adjacent bar, each bar also having vertical teeth at the base of its fork in parallel relation with and inward of the bar extending through the fork, and cam clamps mounted in the extremities of the forks and adjustable to engage the outer edges of the bars respectively extending through the forks to clamp the inner edges of said bars against the teeth of said forked bars respectively.

In witness whereof I hereunto affix my signature.

GEORGE F. NEWTON.
